UNITED STATES PATENT OFFICE

CHARLES A. TJERNBLOM, OF MINNEAPOLIS, MINNESOTA

AUTOMATIC DAMPER

Application filed November 29, 1929. Serial No. 410,373.

This invention relates to automatic dampers controlling the supply of draft air to forced draft furnaces, heaters, oil burners and the like.

- 5 Automatic stokers are now extensively used for supplying the fuel to coal furnaces. Furnaces equipped with automatic stokers are usually of the underfeed type and a draft of air is forced to the fire pot of the furnace 10 generally by use of a blower. The blower, as a rule, is operated only while the stoker is in operation and the stoker is generally controlled by a thermostat to maintain rooms, boilers or the like to be heated at certain temperatures at different times of the day. With 15 the present type of automatic stoker used, there is provided a manually controlled damper regulating the supply of air to the firepot from the blower. When the blower is in operation, it is usually desirable that the damper be opened widely to permit the free ingress of the air from the blower to the fire pot, and when the blower is not in operation, it is desirable that the damper be closed to 20 prevent the natural draft of the fire and chimney from drawing in an oversupply of air to the fire pot. With the manually controlled damper, it is necessary when the fire is banked for the night, that the damper be 25 manually closed off or the natural draft of air will be so great that the fire will be almost completely burnt out before morning, thereby wasting fuel and making it very difficult to start the fire again in the morning. 30 It is also necessary for an attendant to open the damper in the morning before the fire is started.

In forced draft oil burners when the blower or other air forcing means is turned off, it 40 is found that cold air will be drawn into the furnace due to the draft of air in the chimney and this cold air acts to cool the boiler and waste heat.

It is the object of the present invention to 45 provide in combination with a heating furnace, and means for forcing a draft of air to the fire pot thereof, an automatic damper which will act to close off the supply of air to the fire pot, when the means for forcing the 50 air to the fire pot is not in operation and will

act to permit the free ingress of air to the fire pot when the means for forcing air there-to is in operation.

To this end, the invention consists in the novel parts and novel combinations of parts, 55 hereinafter defined in the claims and described in the following specification, made in connection with the accompanying drawings, wherein like reference characters refer to the same or similar parts through the various views and, in which,

Fig. 1 is a view taken chiefly in vertical section through an underfeed heating furnace equipped with an automatic stoker having a blower for forcing a draft of air to the 65 fire pot of the furnace, the air inlet port of the blower being equipped with the automatic damper of the present invention;

Fig. 2 is a plan view of the device illustrated in Fig. 1, certain of the parts being 70 shown in section;

Fig. 3 is a view in side elevation illustrating the automatic damper of the present invention in detached relation;

Fig. 4 is a vertical section taken on the 75 line 4—4 of Fig 3;

Fig. 5 is a horizontal section taken on the line 5—5 of Fig. 3, as indicated by the arrows; and

Fig. 6 is an edge view of a clamping ring 80 that may be used to hold the damper in place on the blower casing, a portion of the ring being shown in vertical section.

Referring to the drawings, portions of an underfeed heating furnace A are illustrated 85 which include a front wall 7 and a rear wall 8 constructed from brick and supporting grate bars 9 also carried by an underfeed fire pot 10. A feed conduit 11 runs through the front wall 7 to the fire pot 10, and a hopper 12 is connected to the outer end of the feed conduit 11 to project upwardly therefrom. An electric motor 13 is supported at one side of the hopper 12 and this motor is adapted to drive 90 through suitable gearing (not illustrated) in-cased in a gear casing 14, a feed screw 15 mounted in the feed conduit 11. An air conduit 16 for supplying a draft of air to the fire pot 10 runs outwardly from the fire pot through the front wall 7 of the furnace and is 100

secured at its outer end to the tangential discharge port of a blower 17 also adapted to be driven through suitable gearing (not illustrated) in the gear casing 14 from the motor 5 13. The blower 17 has a circular air inlet port 17a formed at one side of the blower casing and, as is usual in such constructions, there is a hand operated damper 18 situated in the air conduit 16. The underfeed furnace 10 thus far described is of standard construction and the automatic stoker also is of standard construction, the stoker illustrated being of the type now extensively sold under the trademark "Iron Fireman". 15 In accordance with the present invention, a disk 19 is provided having a rectangular opening in its central portion through which the flanged inner end of a rectangular casing 20 extends. The flanges 20a of the casing 20 may be secured to the disk 19 as by rivets 21. Journaled in the side walls of the casing 20, adjacent the outer open end thereof, are two horizontal shafts 22 and 23 respectively, the shaft 22 being situated adjacent the upper 25 side of the casing and more closely adjacent the open outer end of the casing than the shaft 23. The shaft 23 is disposed approximately centrally relative to the height of the casing. Secured to the two shafts 22 and 23 30 respectively, are upper and lower shutters 24 and 25, the said shutters being formed alike and preferably being composed from rectangular plates having their upper edges bent around the shaft 22 or 23 to embrace the 35 shafts and then riveted to the main portions of the plates. Weights 26 are carried adjacent the lower edges of the two shutters 24 and 25 and these weights, as best shown in Fig. 5, will preferably be of laminated construction composed from a plurality of individual plates 26a. Nutted bolts 27 may be used for securing the weights 26 in place on the shutters and it will be seen that the heaviness of the weights 26 may be variously adjusted by removing or adding additional plates 26a. The lower edge of the upper 40 shutter 24 is disposed inwardly from the shaft 23 and as the upper shutter is of slightly greater width than the spacing between the 45 two shafts 22 and 23, the upper shutter will normally assume the position illustrated in Fig. 4 with the lower edge of the upper shutter bearing against the upper edge of the lower shutter, and with the upper shutter inclining somewhat inwardly. The lower 50 shutter 25 will normally hang vertically downwardly from its shaft 23 to close off the lower half of the opening in the casing 20. The upper shutter 24 will normally, of course, 55 close off the upper half of the opening in the casing. The disk 19 is of such size that it will completely fit over the inlet port 17a at the side of the casing of the blower 17 and the disk may be conveniently applied to the blower 60 casing by means of a ring 28 and screws 29,

the screws extending through suitable openings provided in the ring 28 and disk 19.

The operation of the stoker in conjunction with the automatic damper of the present invention formed by the disk 19, casing 20, 70 shafts 22 and 23, shutters 24 and 25 and weights 26 will be as follows:—

The manually operated hand damper 18 will first be set to regulate the maximum amount of air that can be charged through 75 the air conduit 16 when the blower 17 is in operation. When the blower 17 is not in operation, the shutters 24 and 25 will be held by gravity to practically completely close the air passage to the blower through the casing 20 as shown in Fig. 4. The weights 26 will be sufficiently heavy to hold the shutters 24 and 25 in closed relation even though the heated coal B is burning strongly, the natural draft of hot air up the chimney of 80 the furnace being insufficient to raise the shutters 24 and 25. When the blower 17 is set in operation, the pull of air through the opening in casing 20, will be sufficiently strong to raise the two shutters 24 and 25 to 85 permit of free ingress of air from outside to the blower. If the blower 17 can be operated at variable speeds as is customary in stokers of the type illustrated, the shutters 24 and 25 will be raised varying amounts depending on the speed of the blower. As the upper shutter 24, in its normal position, inclines somewhat inwardly toward the blower, it will be seen that the lower shutter 25 will 90 be more sensitive to the action of the blower than the upper shutter 24. Accordingly, when the blower is operated at extremely low speeds, the lower shutter 25 may be raised somewhat, while the upper shutter 24 is still closed to permit opening of but a small passage-way through the casing 20 for the ingress of air; whereupon when the blower 17 is operated at high speed, both shutters will be raised upwardly to open up a large passage through the casing 20 for the ingress of 95 air to the blower. 100

Green coal C will, of course, be supplied to the hopper 12 and this coal will be fed into the fire pot 10 by means of the screw 15. When it is desired to bank the fire for the 105 night, a large quantity of green coal will be fed to the fire pot. If the hand operated damper 18 was not adjusted to close off the supply of air through the air conduit 16 and the automatic damper of the present invention was not used, the natural draft of air through the conduit 11 and the casing of the blower 17 would be sufficient to quickly burn the banked coal and waste the same, even though the blower 17 be out of operation. By use of the automatic damper of the present invention, it becomes unnecessary to change the position of the hand controlled damper 18 at night when it is desired to bank 120 the fire, and yet the automatic damper will 125 130

act to prevent the natural draft of the fire from drawing air through the conduit 16 and the casing of blower 17 to quickly burn the banker coal. In the morning when a heavy fire is required, it again becomes unnecessary to change the position of the hand controlled damper 18 to secure the heavy fire. It is only necessary that the blower 17 be set in operation, whereupon the shutters 24 and 25 of the automatic damper will quickly adjust themselves to open the passage of air through the casing 20. When the present automatic damper is used, the stoker can be entirely automatically operated, as by thermostatic control, and yet coal will not be wasted. It will, of course, be necessary to keep the hopper 12 of the stoker filled at all times. The present automatic damper acts as a fuel saver and eliminates the necessity for an attendant to go into the furnace room whenever it is desired to vary the heat of a furnace.

It will, of course, be understood that it is within the scope of the present invention to substitute a single shutter or a plurality of shutters for the two shutters 24 and 25 illustrated. It is also possible to provide other types of shutters than the type illustrated for controlling the size of the air passage to the blower automatically as the blower is operated. The position of the automatic damper in the blower casing or in the air conduit can also be varied without departure from the present invention.

Although the automatic damper of the present invention is illustrated in connection with an underfeed coal heating furnace, it can be equally as well applied to overhead feed coal furnaces employing a forced draft, oil burning furnaces and heaters employing a forced draft and other forced draft heating devices.

The present invention is of extremely simple construction and has been successfully demonstrated in actual practice.

It will, of course, be understood that various changes may be made in the form, details, arrangement and proportions of the various parts without departing from the scope of the present invention.

What is claimed is:-

1. A damper comprising a supporting casing through which air is adapted to travel in one direction, an upper damper plate horizontally pivoted in said casing and extending across the same, a lower damper plate horizontally pivoted in said casing and extending across the same, the pivot of said lower plate being slightly spaced from said upper plate in the direction of travel of the air and said upper plate normally resting by gravity in inclined relation against the upper portion of said lower plate, said lower plate being normally held by gravity in substantially vertical position, whereby as air is forced through said casing, said lower plate will

raise for some distance before said upper plate is raised.

2. The combination with an air conduit and air forcing means, of a damper mounted in said conduit and comprising a pair of horizontally pivoted shutters mounted in said conduit to extend across the same, one above the other, weights carried at the lower ends of said shutters and acting to normally hold said shutters by gravity in position to close said conduit, said shutters being adapted to raise to permit the travel of air through said conduit when said forcing means is in operation, one of said shutters being spaced slightly longitudinally of the conduit relative to the other of said shutters and stop means for holding the spaced shutter by gravity in normal position inclined inwardly relative to the travel of air through said conduit, the other of said shutters normally being held by gravity in substantially vertical position, whereby as said air forcing means is set in operation the vertically hanging shutter will raise for a short distance before the inclined shutter will raise.

In testimony whereof I affix my signature.
CHARLES A. TJERNBLOM.
